CLAIM

We claim the ornamental design for a basketball, as shown and described.

DESCRIPTION

FIG. 1 is a front, side perspective view of a basketball; FIG. 2 is a front view of the basketball of FIG. 1; FIG. 3 is a rear view of the basketball of FIG. 1; FIG. 4 is a first side view of the basketball of FIG. 1; FIG. 5 is a second side view of the basketball of FIG. 1; FIG. 6 is an enlarged view of portion 6 shown in FIG. 2; and, FIG. 7 is an enlarged view of portion 7 shown in FIG. 6. The dashed lines shown in FIGS. 1-2 and 4-5 depict portions of the basketball that form no part of the claimed design. The dash dot dash lines in FIGS. 2 and 6-7 are for the purpose of showing the area of enlargement of the basketball and form no part of the claim. The word "Wilson" shown in broken lines is a registered trademark of Wilson Sporting Goods Co. and forms no part of the claimed design.
